UNITED STATES PATENT OFFICE

THEODOR VORCK AND PAUL ZIMMERMANN, OF BARMEN, GERMANY, ASSIGNEES TO
MESSRS. JOHS. GIRMES & CO. AKTIENGESELLSCHAFT, OF OEDT, NEAR KREFELD,
GERMANY

MANUFACTURE OF KNITTED WARP PLUSH

Application filed July 30, 1927, Serial No. 209,426, and in Germany December 2, 1926.

The invention relates to a process for the manufacture of knitted warp plush, and according thereto rib warp threads, or rib weft threads, or both at the same time, are worked into the ground fabric.

The insertion of rib warp threads or of rib weft threads, or of both together, makes it possible to give warp-knitted plush a solidity and rigidity, which makes it more useful for many purposes than heretofore, and also allows it to be used for many purposes for which it has hitherto been useless.

In order that the invention may be clearly understood and readily carried into practice, we have appended hereto one sheet of drawings, in which the figure consists of a diagram, showing, by way of example, the run of the stitches in a fabric made according to the invention.

20 In the example illustrated, the fabric is made up of warp-knitting threads *a*, plush warp threads *b*, rib warp threads *c* and *c'*, and weft threads *d*.

For the sake of clearness the plush thread *b* is only shown in the left-hand longitudinal row or course of stitches. It will be understood, however, that the rib warp thread *c* may be omitted if desired.

The fabric is knitted with the aid of an additional plush needle bar arranged on the appropriate side of the machine.

The warp threads *a* forming the ground of the fabric are shown as forming stitches in two rows, in known manner.

35 The rib warp threads *c* are encircled by loops of the warp threads *a* drawn alternately from right and left of the rib warp threads, so that they are bound into the ground fabric, whilst the rib warp threads *c'* run between the courses of stitches, being held between the meshes *a* between consecutive stitches of the knitting warp threads, and the weft threads *d*.

45 The plush thread *b* is knitted in with the stitches of the warp threads *a* so as also to embrace the rib thread *c*, the consecutive stitches of the thread *b* being engaged with one another, but the thread being drawn out

50 into plush forming loops between the con-

secutive stitches by suitable movements of the thread guides.

The weft threads *d* are shown as inserted between the rib warp threads *c*, *c'* and the knitting warp thread *a*.

55 The machine employed for the manufacture of the fabric may be of any well known and suitable type, but, of course, has its operating mechanism adjusted and arranged to lay the threads in the manner required by the invention.

60 By means of the process according to the invention, it is possible to produce novel kinds of pluses, especially suitable for curtains, wall hangings, or drapings, furniture, upholstery and pillow cases, divan and table cloths, and travelling rugs. Moreover, if india rubber rib warp threads are used, a fabric may be made which is suitable for the manufacture of bandages, corsets, and the like.

65 What we claim is:—

1. Warp knitted plush having a ground fabric of parallel longitudinal courses of stitches, and including warp threads forming meshes passing transversely of the fabric and making consecutive stitches in different courses, plush forming threads knitted into longitudinal courses of stitches to form loops between consecutive stitches of said plush forming threads, weft threads running transversely of the fabric and embraced by stitch loops of the longitudinal courses, and unknitted rib warp threads running between the longitudinal courses of stitches and held in place between the weft threads and the knitted warp thread meshes.

75 2. Warp knitted plush including a ground fabric comprising knitted warp threads in combination with weft threads and unknitted rib warp threads running between the course of warp stitches and held in place between the knitted warp threads and the weft threads, and warp threads knitted into the ground fabric to form plush loops on the surface thereof.

80 3. Warp knitted plush including a ground fabric comprising knitted warp threads in combination with weft threads, unknitted rib warp threads embraced by the stitches of

some of said knitted warp threads, and other unknitted rib warp threads running between the course of warp stitches and held in place between the knitted warp threads and the 5 weft threads, and warp threads knitted into the ground fabric to form plush loops on the surface thereof.

4. Warp knitted plush having a ground fabric of parallel longitudinal courses of 10 stitches, and including warp threads forming meshes passing transversely of the fabric and making consecutive stitches in different courses, plush forming threads knitted into longitudinal courses of stitches to form loops 15 between consecutive stitches of said plush forming threads, and weft threads running transversely of the fabric and embraced by stitch loops of the longitudinal courses.

In testimony whereof we have signed our 20 names to this specification.

THEODOR VORCK.
PAUL ZIMMERMANN.
